WARP STOP MOTION FOR LOOMS

Edwin W. Barrett, Barrington, R. I., assignor to
 Warren Textile and Machinery Supply Co.,
 Warren, R. I., a corporation of Rhode Island

Application November 6, 1935, Serial No. 48,506

5 Claims. (Cl. 139—360)

The present invention relates to the well known mechanical or automatic stop motions which are used in looms for the purpose of stopping the loom when a warp thread breaks or becomes slack.

5 The object of the invention is to provide an improved warp stop motion having advantages over prior constructions as regards its compactness and avoidance of undesired interference with the operations of the loom and of the weaver. 10 Additional aims are to reduce and simplify the number and size of the parts, thereby reducing the cost of manufacture and the effort involved in setting and adjusting the parts into proper working relation, and to facilitate the work of installing a new warp in the loom.

To this end, the invention employs as detectors for the fallen drop-wires the known rocking type of feeler-bars which has the inherent advantage of being responsive with certainty to the fall of the relatively very light and flexible drop-wires necessitated in weaving fine counts of yarn. The parts intermediate the feeler-bars and the loom stopping devices are strong and rigid and positive in their drive and action, and are disposed wholly below the level of the warps and the vibrating lay and the breast beam and close against the side of the loom where they are out of the way of the weaver and of the moving parts of the loom.

30 The parts involved in the driving and in the detecting of the arrest of the feeler-bars by fallen drop-wires are so contrived that the end-frames of the detecting unit or "head" are low and flat and devoid of angles and projecting parts, so that 35 the weaver has free access to the drop-wires to find the fallen one, and the end-frames and their accessories have been simplified so as to occupy the minimum of the available space between the loom sides to afford the maximum amount of 40 room for the drop-wires, a necessity in weaving fabrics having a high count of warps and an advantage in piecing up. Also, the feeler-bars and separating bars are mounted in novel manner permitting quick and easy removal and replacement when a new warp is being inserted, the 45 feeler-bars in particular being arranged to permit of their being withdrawn without displacing their bearing-blocks or swivels from the latters' working positions in the end-portions.

50 Other aims of the invention, and the manner in which these aims are attained, are as set forth hereinafter.

An illustrative embodiment of the invention is shown in the accompanying drawings, in which, 55 Fig. 1 is an end elevation of certain portions at

one side of a loom, showing the organization of the invention applied thereto.

Fig. 2 is a rear elevation of the warp stop mechanism of Fig. 1, without the driving and knock-off connections, and showing its manner of 5 mounting on the loom sides.

Figs. 3 and 4 are an elevation and a plan view respectively of the means for removably retaining the rocking feeler-bars in operating relation in the end-frame. 10

Figs. 5 and 6 are plan and elevational views respectively of similar means for removably holding the feeler-bars in operative relation in the opposite or driving end-frame.

Fig. 7 is a detail showing the manner of driving 15 the rocking bars from the rockshaft.

The detecting unit 1 of the improved warp stop is mounted in usual manner and in usual location on the horns 3 of the loom side, by means of side brackets 5 and intermediate brackets 7 providing 20 for vertical and fore-and-aft adjustment of the unit in the loom. In the hubs 9 of the intermediate brackets are fixed by set screws 11 the supporting shafts 13 on the inward ends of which are fixed by set screws 16 the hubs 15 of the end-frames 17, 19 of the detecting unit. 25

These end-frames 17, 19 are of substantially similar shape, being characteristically rectangular, low, and with their top surfaces flat and devoid of all excrescences. In the upper portion 30 of these end-frames are formed cylindrical holes to serve as bearings for the bearing-members or swivels 21, of known form, the appropriate number of bearings being provided to suit the needs of the particular warp stop motion desired, that 35 illustrated being a four-bank motion. The swivels 21 as usual are slotted at their inward ends to fit the flat sides of the rocking-bars 23 which as hitherto are made out of round stock by flattening two opposite sides thereof, the outward ends of 40 the swivels being counterbored in excess of the diameter of the rocking-bars 23 and provided with integral flanges in the case of the non-driving end shown in Fig. 4, and having integral driving levers 25, Figs. 1 and 7, on the outward ends 45 of the swivels occupying the driving end shown in Figs. 5 and 6, outwardly extending short pins 26 being fixed in the extremities of such levers.

On the outward surface of the end-frame 19 at the non-driving end, as shown in Figs. 2, 3, and 50 4, there is provided a novel bar-retaining member 27 in which are formed holes 29 spaced on centers equaling the spacing-apart of the bearings for the swivels, and hence coinciding with the spacing of the several feeler-bars. These holes 55

are larger in diameter than the rocking-bars 23, but smaller than the outside diameter of the flanges of the bearing members or swivels 21, and the retaining member 27 is also provided with 5 J-shaped slots 31 at each end whereby it is loosely mounted on screws 33 turned part way into low bosses on the two upper corners of end-frame 19 slightly exceeding in height the thickness of the flanges of the swivels. Thus with the rocking-bars in place the retaining member 27 is 10 normally positioned as shown in Fig. 3 with the shanks of the screws 33 occupying the top ends of the J-slots and the holes 29 out of register with the passages through the swivels, so that 15 the bars 23, which extend clear through the swivels, are blocked by the unperforated portion of the retaining member from endwise movement in this direction. But when it is desired to withdraw the bars, in order to insert a new warp, 20 the retaining member is merely shifted manually upward and to the right in Fig. 3, so that the shanks of the screws 33 occupy the lower ends of the J-slots and support the member with 25 the holes 29 in register with the axes of the respective bars 23, which may then be withdrawn endwise outwardly through their swivels and the 30 respective holes 29. Since the flanges on the swivels are larger than the holes 29, these swivels are at all times retained in place, and with 35 avoidance of the effort formerly required to prevent withdrawal of the swivels with the bars, or the nuisance of having them fall out of their bearings or off the bars, to be lost. After the bars are reinserted, the retaining member 27 is restored to its illustrated position in Figs. 3 and 4.

At the driving end, shown in Figs. 5 and 6, a slightly different novel arrangement is provided. Since removal and replacement of the bars will ordinarily be effected at the non-driving end 40 because more easily done where there are no driving parts extending out to interfere, a simple swinging cap 35 is provided having a pivot-pin 37 extending through a hub 39 on the end-frame 17 and secured by a cotter-pin 41. This cap has 45 a finger 43 which engages the flat top surface of end-frame 17 to support this gravitating cap in its normal position shown in Fig. 6 in which the lobes 45 register with the flanges on the driving swivels, blocking egress of the ends of the rods 50 23 in this direction and of course retaining the swivels in their working position in the bearings they occupy in the end-portion 17. When it is 55 desired for any reason to extract the rods and swivels from this end-frame, the swinging cap is merely raised or thrown back out of the way. If the bars alone are to be extracted from this end, the link 47 connecting the levers 25 prevents escape of the swivels from their bearings.

The rocking bars 23 are driven by this connecting link 47, holes in the link receiving the respective pins 26 on the levers, and thus joining the ends of all the levers 25 with the lower end of an arm 49 fixed by screw 51 on a rockshaft 53 journaled in a bearing 55 in one upper corner 60 of the end-frame 17, the link 47 having a pin 57 which extends through the forked lower end of arm 49. The rockshaft 53 terminates just inside of the end-frame 17. This rockshaft is supported near its outer end in a bearing formed 65 in the hub 61 of an arm 63 fixed by means of hub 65 and set-screw 67 to an end of supporting shaft 13 which extends out beyond the loom-side, the rockshaft being retained by a collar 59 set-screwed to it just inside hub 61, and by the hub 70 of arm 49. Outwardly of the arm 63, an arm 69

is fixedly mounted on the rockshaft 53 by means of its hub 71 and a set-screw 73. On the extreme outward end of the rockshaft 53 is mounted the yielding driving arm 75, of known type in which the hub of the arm is free on the rockshaft but is spring-pressed against flat faces of a hub that is fixed on the rockshaft, so as to constitute a give-way whenever the feeler-bars 23 are prevented from rotation through the fall of a drop-wire 77.

A gear 79, Fig. 1, on the end of the cam-shaft 81 outside of the loom side-frame drives a gear 83 of twice its size which is mounted on stud 85 fixed on bracket 87 secured by bolt 89 to the loom side-frame. In gear 83 is fixed a crank-pin 97 on which is mounted rotatively a hub 99 of member 100, in the upper end of which is adjustably mounted through sleeve 102 and set-screw 104 the lower end of drive rod 105, the upper end of which is provided with an eye and connected to driving lever 75 by a stud 107 adjustably fixed in the slot of the lever. Thus the drive rod 105 yieldingly imparts a rocking movement of rockshaft 53 in both directions.

Since all the feeler-bars 23 are positively linked together and to the driving rockshaft 53, the arrest of one feeler-bar by a fallen drop-wire arrests the whole mechanism as far as the arm 75 of the give-way.

From the fixed arm 69 on rockshaft 53 depends 30 a lifter wire 108, having its upper end hooked through a slot in the end of arm 69, and having its lower end run through a hole in a sleeve 110 on a member 112 pivoted at 114 to a constantly 35 vibrating hook 116 which comprises the striker of the knock-off mechanism provided to actuate the loom stop mechanism comprising the usual power-unshipping and brake mechanism, of which only the familiar shipper-handle 118 on its rockshaft 120 is indicated, the remaining parts 40 being well known and unnecessary to be described herein in order to understand the present invention.

The vibrating hook or striker 116 is pivoted at its forward end at 122 to the upper end of a 45 lever 124 pivoted on a pin 126 on bracket 87, the lower end of the lever being held against a cam 128 on the outward face of gear 83 by a contracting spring 130 anchored at 132 to a fixed part and attached at its other end to a short arm 50 134 integral with lever 124 and extending at right angles to the extent thereof. The loom stopping rockshaft 120 has fixed on its end an arm 136 to the free end of which is pivoted a push-rod 138 slidable fore-and-aft the loom in suitable 55 guideways (not shown) and passing through an opening 139 in the upper end of lever 124; its rearward end carries a tooth 140 for engagement by the hook 116 when the loom is to be stopped by a fallen drop-wire, this tooth being mounted 60 on the push-rod 138 by means of an aperture 142 formed in the tooth and through which the rod extends, and yieldingly located in the desired position through being pivoted at 144 to a member 146 clamped on the rod by means of its hub 65 148 and set-screw 150, a spring 152 being attached to the tooth at 154 and to member 146 by means of bolt 156, whereby the tooth 140 is held firmly but yieldingly against hub 148.

The hook 116 is adjusted by means of screw 70 158 bearing on shelf 160 on the lever 124, and by adjustment of a collar 162 set-screwed to lifter-wire 108 below the sleeve 110, so that uninterrupted rocking motion of driving rockshaft 53 and hence of lifter-arm 69 will lift the hook or 75

striker 116 during its forward stroke in time to prevent it from engaging tooth 140, whether rockshaft 53 is rotating in either direction; but the adjustment and timing are such that if a 5 feeler-bar 23 is checked by a fallen drop-wire the resulting arrest of driving rockshaft 53 will leave the engaging point of the hook below the level of the corresponding engaging portion of tooth 140, so that the ensuing engagement and 10 the continuing forward movement of the continuously going hook 116 will pull forward the push-rod 138 and knock off the loom.

A novel method has also been provided for removably mounting the back stop or separating 15 bars 163, Figs. 1 and 2, which hold the lower ends of the drop-wires against rotation with the rocking feeler-bars 23 when they fall. In accordance with this phase of the invention, the ends of the separating bars are cut to form a step at 20 165, and the end-frames 17, 19, of the detecting unit 1 are formed with slots 167 fitting closely in their width the horizontal thickness of the bars 163, having a horizontal bottom 169 and an inwardly and upwardly slanting top 171, with 25 the total clear height of the opening slightly in excess of the vertical dimension of the tallest bars 163 to be used. This arrangement makes it possible to insert the bars vertically, through merely running one end through its proper slot 30 far enough so that the other end can descend within the end-frame nearest it, thereafter moving the bar endwise in the opposite direction until the vertical portion of the step brings up 35 against the inward face of the adjacent end-frame and the horizontal portion of its step rests upon the bottom 169 of the appropriate slot in that end-frame, the remote end automatically assuming a corresponding relation with its end-frame, reversing the procedure in obvious manner to remove the bar. By this construction, the 40 whole of the space between the inward surfaces of the end-frames is available for drop-wires, instead of having to sacrifice a certain amount of the width of the loom to provide for projecting 45 bar-supports as heretofore, as well as greatly facilitating the removal and replacement of the bars instantly for installation of a new warp.

While I have illustrated and described certain forms in which the invention may be embodied, I am aware that many modifications may 50 be made therein by any person skilled in the art,

without departing from the scope of the invention as expressed in the claims. Therefore, I do not wish to be limited to the particular forms shown, or to the details of construction thereof, but

What I do claim is:—

1. In a warp stop motion, in combination, a feeler-bar of non-circular cross-section, a cylindrical bearing block supporting an end of such bar, a bearing for such block, a movable device normally effective to prevent longitudinal removal of the bar from the block, but movable into a position permitting such removal of the bar while preventing removal of the bearing block, and stop means locating said device in such position. 10

2. In a warp stop motion, in combination, at least three feeler-bars of non-circular cross-section, cylindrical bearing blocks supporting the ends of such bars, bearings for such blocks, and a device normally effective to prevent removal 20 of both the bars and the bearing blocks and movable into a position in which it permits removal of all the bars while preventing removal of any of the bearing blocks. 15

3. In a warp stop motion, in combination, feeler-bars of non-circular cross-section, cylindrical bearing blocks supporting the ends of such bars, bearings for such blocks, and a device normally blocking endwise movement of a feeler-bar and its bearing-block in one direction and having an 25 aperture through which the bar can pass and the bearing cannot, the device being movable to bring such aperture into register with the bar. 30

4. In a warp stop motion, in combination, drop-wires, feeler-bars, backstop bars supporting the drop-wires against movement by the feeler-bars, and an end-frame having a single plane inward face in which the feeler-bars and backstop bars are supported, the end-frame having slots therethrough, and the backstop bars 40 having stepped end-portions received in such slots. 35

5. In a warp stop motion, in combination, drop-wires, feeler-bars, backstop bars supporting the drop-wires against movement by the feeler-bars, 45 and end-frames supporting the feeler-bars and backstop bars and having slots permitting passage of the backstop bars entirely through the end-frames in moving the latter bars into and out of operative position. 50

EDWIN W. BARRETT.
